UNITED STATES PATENT OFFICE.

CLARENCE B. FOWLER, OF NEW YORK, N. Y., ASSIGNOR TO WESTERN ELECTRIC COMPANY INCORPORATED, OF NEW YORK, N. Y., A CORPORATION OF NEW YORK.

OPERATOR-INSTRUCTION CIRCUITS.

Application filed December 31, 1919. Serial No. 348,577.

To all whom it may concern:

Be it known that I, CLARENCE B. FOWLER, a citizen of the United States, residing at New York, in the county of New York, State 5 of New York, have invented certain new and useful Improvements in Operator-Instruction Circuits, of which the following is a full, clear, concise, and exact description.

This invention relates to a telephone exchange system and more particularly to an arrangement of circuits for instructing operators in the method of extending calls from a manual office to an office or exchange provided with mechanical switching equipment.

The object of the invention is the provision of circuits and apparatus for instructing operators in the extension of calls to offices having mechanical equipment and in 20 the practice of correctly dialing the numbers of subscribers in such offices.

One feature of the invention resides in the provision of means for indicating to an instructing operator the character of each digit 25 dialed by a pupil operator in accordance with instructions given the latter by the instructor.

A further feature of the invention resides in the provision of a group of special trunk 30 circuits and apparatus arranged to simulate interoffice trunks for the instruction of operators in making the group busy test of interoffice trunks. For a complete disclosure of the invention reference should be 35 made to the following description considered in connection with the accompanying drawing illustrating one specific embodiment of the genus of the invention.

The drawing discloses one cord circuit of 40 an operator's position O equipped with an impulse-sending device of the dial type by means of which calls may be extended to an office provided with mechanical switching equipment; the first and last trunks of the 45 group of trunks extending to an instructing operator's position together with apparatus associated therewith; and an indicating device at the instructing operator's position for indicating to the instructor the digits dialed 50 by the operator in accordance with her instructions.

A more comprehensive understanding of 55 the invention may be had from a consideration of the organization of the circuits and the manner in which they are employed. It

will be assumed that an instructing operator whose cord circuit is partially disclosed at O' is assigned to instruct a new operator who is provided with standard dialing cord circuits such as disclosed at O, in the method 60 of extending calls from a manual office to an office equipped with mechanical switching equipment. Following the instructions given by the instructor to the new operator in any approved manner as over the well-known order wire circuit, the operator picks up the calling plug P of an idle cord circuit at her position, in the case assumed the plug of cord circuit O, and tests the first jack terminal of a group of trunks T' . . . T¹⁰ extending 65 to the instructor's position. These trunks are preferably arranged in groups of ten and are designed to simulate at their outgoing ends interoffice trunks such as would be employed between a manual and an 70 automatic office. Each trunk is provided with multiple calling jacks appearing at a plurality of operator's positions and with multiple jacks at a plurality of instructor's 75 positions.

If when testing the first trunk circuit T' of the group all of the trunk circuits are busy and consequently the sleeve relays of all trunks of the group are energized, the operator receives a group busy tone over a circuit 80 extending from ground, through the secondary winding of the busy tone coil 2 through the outer armature and front contact of the sleeve relay 3 of the last trunk of the group, thence serially through the outer 85 armatures and front contacts of the sleeve relays of the remaining trunks of the group to the sleeve 4 of jack J' of the first trunks of the group and thence through the tip of the plug, the back contact and armature of the 90 cord sleeve relay 5 and to the test winding (not shown) of the operator's set. The operator, upon receiving the tone, is apprised of the fact that all trunks of the group are 95 busy.

If there is an idle trunk in the group the operator does not receive the tone test since the tone circuit is open at the contacts of the sleeve relays 3 of all idle trunks. In the event that the first trunk T' of the group is 100 busy by reason of a connection thereto of another cord circuit similar to the cord circuit O, the operator will find the usual busy potential on the sleeve of the multiple jack and will receive a click in her receiver when 105 110

she tests the multiple jack with the tip of the calling plug. Upon receiving the busy click she will then proceed to test the trunks in order until an idle trunk is found, when 5 she will proceed to establish a connection therewith by inserting the calling plug of the cord circuit O into the jack of the idle trunk.

It will be assumed that connection is thus 10 established with the last trunk T^{10} of the group. The insertion of plug P in the jack J^{10} of this trunk establishes a circuit for the sleeve relay 3 of the trunk which may be traced from grounded battery, through the 15 calling supervisory lamp 6, sleeve relay 5 of the cord circuit, the sleeve of plug P and jack J^{10} and thence to ground through the sleeve relay 3. Relays 5 and 3 are energized in this circuit, relay 5 disconnecting the tip 20 of the plug from the testing lead 7 and connecting it to the tip strand of the cord circuit, and relay 3 establishing a circuit for the trunk signals 8 appearing before a plurality of instructing operator's positions.

25 The instructing operator, who at the time has been assigned for instructing the new operator, upon noting the operation of trunk signal 8, plugs the answering plug of her cord circuit O' into the answering jack 30 of the trunk circuit indicated by the operated signal 8, and by means of listening key 9, connects her telephone set to the trunk circuit for transmitting instructions over the selected trunk circuit to the operator.

35 The connection of cord circuit O' to the trunk T^{10} causes the energization of the calling supervisory relay 11 in the cord circuit O , over the circuit extending from grounded battery at cord circuit O, through

40 the winding of relay 11, lower normal contacts of ringing key 12, and dialing key 13, ring contacts of plug P and jack J^{10} , lower conductor of trunk T^{10} , thence by the crossover conductor 14 to the upper conductor of 45 the trunk, through the tip contacts of the jack and plug at the instructing operator's position to ground, the trunk conductors being reversed as at 14 to cause the cord circuit batteries to be connected in series for

50 the purpose of permitting supervision in the cord circuits. The energization of relay 11 causes the shunting out of lamp 6 in the usual manner to signal the operator that the connection has been cut through.

55 The operator thereupon throws listening key 15 to connect her set (not shown) to the cord circuit O and receives instructions for dialing from the instructor over the trunk circuit. It will be assumed, for the 60 purpose of illustration, that the operator receives instructions to dial the number 25. She thereupon throws the dialing key 13 for connecting the sender S to the tip and ring contacts of the plug P and proceeds to 65 set the dial for the first digit 2. As soon as

she tests the multiple jack with the tip of the key 13 is thrown, a circuit is established for the line relay 16 of the indicating device D associated with the instructing operator's position, which circuit may be traced from grounded battery, through the 70 winding of relay 16, over conductor 17, through contacts 18 of the dialing key 13 and thence to ground through the impulse contacts 19 of the sender S. Relay 16, upon energizing, establishes a circuit extending from its armature and front contact and through the winding of slow to release relay 20. Relay 20, upon energizing, establishes a circuit for the second slow-to-release relay 21, which may be 80 traced from grounded battery, through the armature and front contact of relay 20, the winding of relay 21 and thence to ground through the back contact and armature of relay 22. The circuits of the indicator are 85 now prepared for the reception of the first series of impulses corresponding to the first digit dialed by the operator.

Upon the release of the dial of sender S, the dial returns to normal and in the usual 90 manner causes two interruptions of the impulse contacts 19. Upon the first interruption of these contacts, the circuit above traced for the line relay 16 is opened and the line relay momentarily deenergizes 95 closing at its armature and back contact a circuit extending from grounded battery, through the armature and back contact of the upper counting relay #1, through the winding of the lower counting relay #1' and thence to ground at the front contact and armature of relay 21. The #1' counting relay, upon energizing, prepares a locking circuit for itself extending from ground at the armature and contact of relay 21 through the 100 winding of relay #1', its upper armature and front contact and the winding of the #1 counting relay to grounded battery. The #1 counting relay, however, does not energize at this time since its winding is 105 shunted by battery connected through the armature and back contact of line relay 16. As soon, however, as the circuit over conductor 17 is reestablished following the first interruption of the circuit at impulse contacts 19 of the sender S, relay 16 reenergizes, disconnecting battery at its armature and back contact from one terminal of the winding of the #1 counting relay, whereupon the #1 counting relay energizes, opening at its armature and back contact the circuit over which the #1' counting relay was energized and extending the initial energizing circuit through the armature and back contact of the #2 counting 115 relay, through the winding of the #2' counting relay to ground at the armature and front contact of relay 21. Counting relay #1' also closes at this time a circuit 120 extending from ground, through the lamp 130

- 26, the lowermost armature and front contact of relay #1, the lower armatures and back contacts of the counting relays #2' and O', through the winding of slow-to-
 5 energize relay 23, to battery at the armature of relay 16, but as there is but a short interval between impulses, counting relay #2' energizes on the next impulse before lamp 26 or relay 23 have time to operate.
- 10 Upon the second interruption of the circuit over conductor 17, the #2 counting relay energizes, locking up through the winding of the #2' counting relay as previously described in connection with the #1 and
 15 #1' counting relays.
- Following the second interruption of the stepping circuit, relay 16 again energizes and since the dial has now returned to its normal position, relay 16 is maintained energized for an appreciable time or until the operator has set the dial for the second digit. During this interval a circuit is established for the slow-to-energize relay 23, which may be traced from grounded battery, through
 20 the armature and front contact of relay 16, through the winding of relay 23, through the lower armatures and back contacts of the lower counting relays #3' to #O' inclusive, the lower armature and front contact of the #2' counting relay and through the indicating lamp 24 to ground. Since this circuit is maintained for a sufficient interval for the relay 23 to energize, the lamp 24 is lighted sufficiently to give the instructor a signal that the operator has dialed the digit 2. Upon the energization of relay 23, a circuit is established for the slow relay 22 which may be traced from grounded battery, through the armature and front contact
 25 of relay 16, winding of relay 22 and thence to ground at the armature and front contact of relay 23. Relay 22, upon energizing, opens the circuit for relay 21 which, after an interval, deenergizes, opening
 30 at its armature and front contact the locking circuits for counting relays #1, #1', #2 and #2', which thereupon deenergize, restoring the circuits of the indicator to normal position.
- 35 In the same manner the operator dials the second digit 5, causing the counting relays #1', #2', #3', #4' and #5' to be energized and locked up in a circuit extending through the armature and front contact of relay 21 and, following the series of five impulses, the lamp 25 becomes lighted in series with the relay 23 to indicate to the instructor that the operator has dialed the digit 5 in accordance with her instructions.
- 40 The energization of relay 23 again causes the energization of relay 22 and thereby, the restoration of the energized counting relays to their normal position.

From the foregoing description it is ap-

parent that the indicator D is successively 65 operated to indicate the several digits dialed by the operator and thus indicates to the instructor whether the operator is following the instructions given to her and thus affords an accurate check on the efficiency of 70 the operator and the speed with which she carries out the instructions given to her.

What is claimed is:

1. In a telephone system, an operator's position, an instructor's position, means for 75 establishing an instruction circuit between said positions, means for transmitting dialing instructions from said instructor's position to said operator's position, an impulse sender at said operator's position, an indicating device at said instructor's position and means for operating said device in accordance with the operation of said impulse sender. 80

2. In a telephone system, an operator's position, an instructor's position, means for establishing an instruction circuit between said positions, means for transmitting dialing instructions from said instructor's position to said operator's position, a dialing 90 device at said operator's position, an indicating device at said instructor's position and means for successively operating said indicating device in accordance with successive operations of said dialing device. 95

3. In a telephone system, an operator's position, an instructor's position, means for establishing an instruction circuit between said positions, means for transmitting dialing instructions from said instructor's position to said operator's position, a dialing device at said operator's position, an indicating device at said instructor's position and means for enabling successive operations of said indicating device in accordance with 100 successive operations of said dialing device over a circuit independent of said instruction circuit for indicating the several digits of a line designation assigned by said instructor. 105

4. In a telephone system, an operator's position, an instructor's position, means for establishing an instruction circuit between said positions, a dialing device at said operator's position, an indicating device at said 110 instructor's position comprising a plurality of indicating lamps and counting relays, and means for successively operating said relays to selectively light said lamps in accordance with the setting of said dialing 115 device over a circuit independent of said instruction circuit. 120

5. In a telephone system, an operator's position, a cord circuit thereat, an instructor's position, means including said cord circuit for establishing an instruction circuit between said positions, a dialing device at 125 said operator's position, a key for associat-

ing said device with said cord circuit, an indicating device at said instructor's position, and means for operating said indicating device in accordance with the setting of 5 said dialing device over a circuit independent of said instruction circuit and extending through contacts of said key.

6. In a telephone system, an operator's position, a cord circuit thereat, an instructor's position, means including said cord circuit for establishing an instruction circuit between said positions, a dialing device at 10 said operator's position, a key for associating said device with said cord circuit, an indicating device at said instructor's position, and means for operating said indicating device in accordance with the setting of 15 said dialing device over a circuit extending through contacts of said key and 20 through the impulse contacts of said dialing device.

7. In a telephone system, an operator's position, an instructor's position, means for establishing an instruction circuit between 25 said positions, a dialing device at said operator's position, an indicating device at said instructor's position adapted to be operated in accordance with impulses transmitted by said dialing device, comprising 30 an impulse relay, a train of counting relays adapted to be energized in succession in response to the operation of said impulse relay and locked in their operated positions, a group of lamps adapted to be selectively 35 operated by said counting relays, and means effective upon the termination of said impulses for unlocking said counting relays

and for illuminating the lamp selected by the last energized relay of the train.

8. In a telephone exchange system, an 40 operator's position, a group of trunk circuits thereat, a sleeve relay associated with each trunk circuit, a tone circuit extending from the sleeve terminal of the first trunk circuit of the group serially through alternate contacts of all of 45 said relays, and a source of tone current for connection to said circuit.

9. In a telephone system, an operator's position, an instructor's position, a group of 50 trunk circuits extending between said positions, a sleeve relay associated with each trunk circuit at said operator's position, a tone circuit extending from the sleeve terminal of the first trunk circuit of the group 55 serially through alternate contacts of all of said relays, and a source of tone current for connection to said circuit.

10. In a telephone system, an operator's position, an instructor's position, a group of 60 trunk circuits extending between said positions, a sleeve relay associated with each trunk circuit at said operator's position, a trunk signal under the control of each relay at the instructor's position, a tone circuit 65 extending from the sleeve terminal of the first trunk circuit of the group serially through alternate contacts of all of said relays, and a source of tone current for connection to said circuit. 70

In witness whereof, I hereunto subscribe my name this 30th day of December, A. D. 1919.

CLARENCE B. FOWLER
